UNITED STATES PATENT OFFICE.

ERNEST WINNE, OF NEW YORK, N. Y.

FOUNTAIN-PEN.

1,181,101.

Specification of Letters Patent. Patented Apr. 25, 1916.

Application filed May 29, 1914. Serial No. 841,796.

To all whom it may concern:

Be it known that I, ERNEST WINNE, a citizen of the United States, and a resident of New York city, borough of Manhattan, in the county of New York and State of New York, have invented certain new and useful Improvements in Fountain-Pens, of which the following is a specification.

This invention relates to certain new and useful improvements in fountain pens, and particularly to that class of fountain pens which are provided with an automatic filling device composed of an ink reservoir and means for excluding the air from the ink reservoir so as to permit the ink to flow in.

The object of my invention is to provide a new and improved pen of this kind which is simple in construction, capable of being manipulated with least possible expenditure of time and effort, which does not require the detaching or preliminary shifting of any parts, which does not have any parts projecting from the side of the barrel that would in any way interfere with the convenient holding of the pen when in use, and in the operation of which there is no tendency to force the pen point against the bottom of the ink well.

In the accompanying drawings in which like letters of reference indicate like parts in all the figures:—Figure 1 is a longitudinal sectional elevation of that end part of a fountain pen opposite the one in which the pen point is held, showing one embodiment of my invention. Fig. 2 is a side view of the cup shaped cam. Fig. 3 is a plan view of the same. Fig. 4 is a sectional view on the line $a-a$ of Fig. 1.

The fountain pen has the usual barrel 1 made of hard rubber or similar substance, and, in the embodiment shown, the barrel contains a soft rubber ink reservoir 2 which can be compressed by means of a pressure bar mechanism operated by a plunger 3 that is guided and mounted in the end of the barrel 1 to slide lengthwise of said barrel, the outer end of the plunger 3 normally being held a short distance beyond the end of the barrel 1 by the spring of the mechanism beneath.

The combination of the barrel 1, the elastic ink reservoir 2, the plunger 3 and the pressure bar mechanism it operates, I do not claim as my invention, as this is old and well known and one example of which pressure bar mechanism is shown in the Patent

No. 787,152 issued April 11, 1905, to John Davison, self filling fountain pen.

On the end part of the barrel 1 a tubular extension piece 4 is held, preferably by screwing it on the end of the barrel, and this extension piece is provided at its outer end with an inwardly extending bearing ring 5, which is screwed into the outer end of the extension 4. A plug 7 fits snugly and movably within the opening formed by the inner edge of the ring 5 and extends into the extension 4 and also beyond the outer end of the same. On the outer end of said cylindrical plug 7 a cap 8 is secured, preferably by means of a pin 9 passed transversely through the cap and the plug—the inner end of the cap resting against the outer end of the tubular extension 4. In order to permit of obtaining a better hold on the cap 8, it is preferably knurled or roughened as indicated at 10.

From the cylindrical plug 7, two or more projections 11 extend laterally and rest upon the bearing ring 5. A cup-shaped cam 80 piece 12 fits over the inner end of the plug 7 and is prevented from turning on the axis of the barrel by a pin 13 which is passed through the walls of the tubular extension 4 and through slots 14 in the cup-shaped cam 12, so that this cup-shaped cam can move only lengthwise of the tubular extension 4 in which it is contained. The closed end of the cup-shaped cam rests against the outer end of the plunger 3 and is normally held in place by the outward pressure of the plunger as above referred to. The cup-shaped cam is provided at the edges of its flanges or side walls with cam edges 15, of which there are four in the embodiment 90 shown, and these cam edges are pressed, by the above mentioned pressure of the plunger 3 upon the ring 5, and upon the projections 11. If now the cap 8 is turned axially, the plug 7 and the projections 11 thereon travel with it, as indicated by the arrow x' in Fig. 2, and, acting on the cam edges of the cup-shaped cam 12, force said cam 12 lengthwise of the plug as indicated by the arrow x^2 in Fig. 2, and thereby 100 the plunger is forced in the same direction, which in turn causes the pressure bar to bear on the flexible ink reservoir, compresses the same more or less, and forces out some or all of the air that may be in said reservoir. When the projections 11 arrive at 105 the highest points of the cam edges 15, they

snap off and into the open ends of the grooves 14 as indicated in Fig. 2, thus permitting the elastic pressure of the plunger and mechanism beneath to show the cam in the inverse direction of the arrow α^2 , Fig. 2. By the expansion of the compressed reservoir, which is now possible, as the pressure exerted by the cam and the projections 11 on the plunger 3 has been removed, the air 10 is rarefied in the flexible reservoir and the exterior air pressure forces the ink, into which the pen point has been dipped, into said reservoir and fills the same. Therefore all that is necessary to fill the reservoir is 15 to give the cap 8 a quarter turn axially of the barrel—as thereby the cup-shaped cam 12 and the plunger 3 are first gradually forced toward the pen point, thereby forcing the air out of the flexible reservoir, and 20 then the cup-shaped cam is released and thrown back and the reservoir fills with ink.

It will be observed that the means for filling the pen merely form a slight extension at the upper end of the barrel, and that 25 all parts are substantially flush and in line, and that no parts project from the barrel of the pen that could be accidentally operated, as the only way of filling the pen is by giving the cap 8 a greater or less turn axially, 30 which requires the application of more or less force. No parts must be first removed and later on replaced for the purpose of filling the pen; neither is it necessary to reverse the movement, but merely to give the cap 8 35 a quarter turn to the right until the mechanism snaps into its normal position. Also, as the operation of this mechanism requires no longitudinal pushing or pulling, there is 40 therefore no tendency to injure the pen point by forcible contact with the bottom of the ink well.

Having described my invention, what I claim as new and desire to secure by Letters Patent is:—

45 1. In an automatic filling fountain pen, the combination with a barrel, a compressible reservoir in the barrel, and a plunger for action on said reservoir, of a cam piece mounted in an end part of the barrel to move longitudinally and to act on said plunger, a member mounted to rotate axially in 50 the end of the pen barrel and having means

acting on said cam piece to move the same lengthwise of the barrel, said cam piece having means to prevent rotation of the member in one direction, substantially as set forth. 55

2. In an automatic filling fountain pen, the combination with a barrel, a yielding ink reservoir and a plunger for action on 60 said reservoir, of a cup-shaped cam piece mounted in the end part of the barrel, a pin for guiding the cam piece in its movements lengthwise of the barrel and to prevent rotative movement of the cam piece, a 65 plug projecting into the cam piece and having lateral projections to act on the cam edges of the cam piece, and a cap on said plug for turning it, substantially as set forth. 70

3. In an automatic filling fountain pen, the combination with a barrel, a yielding reservoir and a plunger for action on said reservoir, of a cam piece adjacent to said plunger, which cam piece is mounted to 75 move lengthwise of the barrel, a plug having projections extending beneath the cam edges of the cam piece, a bearing ring in the barrel, on which bearing ring the projections rest, substantially as set forth. 80

4. In an automatic filling fountain pen, the combination with a barrel, a yielding reservoir therein, a plunger mounted in the end of the barrel for action on said reservoir, of an extension piece screwed on the 85 end of the barrel, an inwardly extending bearing ring on said extension piece, a cup shaped longitudinally movable cam piece in said extension of the barrel, a plug mounted rotatively in said extension, 90 and extending into the cam piece, lateral projections on said plug, which projections can act on the cam surface of the cam piece, said plug projecting beyond the outer end of the extension piece, substantially as set 95 forth. 80

Signed at New York city, in the county of New York and State of New York this ninth day of May, A. D. 1914.

ERNEST WINNE.
